UNITED STATES PATENT OFFICE.

JAMES H. RAND, OF NORTH TONAWANDA, NEW YORK.

INDEX.

Application filed April 14, 1922. Serial No. 552,788.

To all whom it may concern:

Be it known that I, JAMES H. RAND, a citizen of the United States of America, and resident of North Tonawanda, in the county 5 of Niagara and State of New York, have invented new and useful Improvements in Indexes, of which the following is a specification.

This invention relates to index devices of 10 the type having movable index holders or panels for displaying the classified subject-matter of the indices and more particularly to that type in which the index supports are mounted to swing vertically into and out 15 of a frame in which a plurality of such supports are arranged in juxtaposition on a pivot substantially perpendicular thereto.

The principal objects of the invention are to provide a device of the class referred to 20 in which index panels of great capacity are compactly arranged, to mount such panels in a manner to render them readily accessible for reference or changes, to provide supports for the panels when nested within 25 the frame in housed position and when swung to extended position outside of the frame for inspection, to protect the index material against displacement and injury as the panels are swung from one position to 30 the other, to provide for ready removal and rearrangement of the index panels as well as of the index material, to provide index panels blanked from sheet material and having a peripheral flange which extends beyond and 35 protects the index material, to provide reinforcing members for such index panels which in addition space and carry the holding means for the index material, to furnish suitable tabs for the index panels which 40 may be grasped to swing the panels into extended position, and in general to produce a device which is generally superior to prior devices of this kind.

The genus of the invention is illustrated 45 by the concrete embodiment shown in the accompanying drawings, in which,—

Fig. 1 is a side elevation showing the index panels in dotted line;

Fig. 2 is a front elevation;

Fig. 3 is a view similar to Fig. 1 showing one panel in extended position and a second panel partially swung to extended position;

Fig. 4 is an enlarged detail plan view of 55 the pivot corner of the holder;

Fig. 5 is a sectional view on the line 5—5 of Fig. 4;

Fig. 6 is a sectional view on the line 6—6 of Fig. 4;

Fig. 7 is a detail view of the blank from 60 which the panel is made before shaping;

Fig. 8 is a plan view of another portion of the index panel;

Fig. 9 is a sectional view on the line 9—9 of Fig. 8; 65

Fig. 10 is a detail plan view of the index panel; and

Fig. 11 is a sectional view on the line 11—11 of Fig. 10.

The embodiment of the invention chosen for the purpose of illustration comprises an index device having a frame A in which a plurality of large index panels B are mounted. The frame A is generally rectangular in form and comprises a base 12, back 13, and parallel sides 14 and 15. Removably mounted in aligned openings 16 in the sides 14 and 15 adjacent to the lower front corners thereof is a rod 17 having an axial threaded recess at each end in which is normally threaded an axial extension on the retainers 18, which have a peripheral flange 19 engaging sides 14 and 15, respectively. By removing one of the retainers 18, the rod 17 can be withdrawn through the opening on the other side for the removal or insertion of the holders. 70 75 80 85

Index panels B have pivotal engagement with rod 17 for swinging movement in planes substantially perpendicular thereto by the 90 provision of apertures b in said holders (Fig. 4). As shown this aperture is disposed adjacent to one corner of the panels so that in one position the latter are contained wholly within frame A, and when 95 swung to extended position (Fig. 3) they are exposed throughout the greater part of their surface for the inspection of the index material thereon. As shown in Figs. 1 and 3, base 12 extends somewhat beyond the rest of the frame at the front, and is provided near its front and rear edge with elongate yielding bumpers 20, preferably of rubber, which cooperate with the rod 17 to support index panels B in both their housed and extended 100 105 positions. 20' is a similar bumper.

To assist in retaining panels B in upright position, partition members 21 are provided in frame A. These partitions fit into grooves 22 and 23 in base 12 and end 13, respectively, 110

and abut against screws 24 which are threaded into bushings 25 in the base and end respectively, these bushings having slots registering with grooves 22 and 23 respectively 5 to receive the partitions. By setting up screws 24, partitions 21 may be forced upwardly and forwardly as desired, thereby properly to position the partitions in the frame A.

10 The construction of the index panels B will now be described, reference being had to Figs. 4 to 9 inclusive. These panels are blanked from sheet material, preferably aluminum, a portion of the blank adjacent 15 to the corner having the pivotal openings b, being shown in Fig. 7. As indicated at e the blank is recessed at the corners and the bent-wire corner member 26 having reduced ends 27 (Fig. 4) is so positioned that the 20 unreduced portion of the member rests in the opening. The marginal portions d are then rolled and bent upon the blank a in a manner to form a peripheral tubular flange 28, the free edge of the marginal portions 25 being bent at right angles to form an inner wall 29 for the flange, so that the flange forms a closed channel e, Fig. 9, entirely around the periphery of the holder. In this channel e the reduced ends 27 of corner 30 members 26 are received, the tongues f and g in the blank (Fig. 7) adjacent to members 26 being inwardly bent from each side to wedge member 26 securely in place as indicated in Fig. 6.

35 The marginal flange on that portion of the holder which is hidden within the frame, when the holder is in extended position, is of substantially the width of the portion hidden and is much wider than the flange about 40 the other sides as indicated by 28^a in Fig. 4. For the purpose of strengthening this wide flange 28^a particularly about pivot opening b a filler 29 consisting of a piece of wood, sheet of cardboard, fibre or the like, is provided which entirely fills channel e. Opening b then extends entirely through flange 28^a through the filler 29 and the back plate a of the holder and is provided with an eyelet 30 providing a pivot bearing.

50 Previous to the bending of the marginal portions of the blank to make flange 28, a plurality of strips 31 of any suitable material, preferably metal, are attached to blank a in a manner to extend beneath the 55 top and bottom portion of the peripheral flange as indicated in Fig. 11. The method of attachment here shown is by rivets or eyelets 32 substantially midway of each strip and spaced from the edges thereof (Fig. 3). 60 Spring clips 33 shown in section in Fig. 9 each consisting of an elongate strip of metal folded upon itself at 34 to form a spring retaining end, and again at 35 to form a base, are frictionally engaged over the side faces 65 of strips 31. Strips 31 are so disposed as to

position spring clips 33 in abutting relationship with each other or with the marginal flanges 28, as shown in Figs. 3 and 9. Spring retainers 33 serve to hold the index strips or cards in position. Since the index 70 device herein shown is intended for relatively permanent records, large index cards h are shown of such size that three completely cover each of strips 31 as shown in Fig. 3. It is to be understood, however, that 75 cards or strips of any suitable or desired width may be used.

To serve as a guide as to the index material upon each of the index holders B and further to serve as a convenient means for 80 grasping the holder to swing it to extended position, tabs 40 of any suitable material, preferably metal are made fast to the outer edge of each of the holders B as indicated in Figs. 1, 3, 10 and 11. As shown in Fig. 85 11, tab 40 has a hook member 41 adapted to hook under flange 28, the inner face 29 of which is cut away a sufficient distance. The tab 40 is bent to tubular form and comprises the part 42 so disposed that when end 41 is hooked under flange 28 part 42 frictionally engages the outer edge of the holder B firmly to retain the tab in position. The tab is preferably entirely enclosed in a sheath 43 of transparent material, such as 90 celluloid to protect the index slip 44 movably received between the sheath and the tab. Such transparent material naturally tends to bow out from the adjacent wall of 95 the tab and in order to cause the index slip 44 to have a rounded contour, and thus be more easily visible, a resilient element such for example as a folded card 45 may be inserted therebehind as shown in Fig. 11 to hold the 100 slip in contact with the inner surface of the bowed portion of the tab. As indicated in Fig. 1 tabs 40 on successive holders B are 105 progressively spaced at progressively greater distances from the top of the frame for convenience in reading the index cards thereon. 110

To further index the material on the holders, index strips 50 are provided at the bottom of each column of index cards, as shown in Fig. 3. These strips are frictionally retained in place by clips 33 and are 115 preferably protected by a celluloid sheath 51 (Fig. 11).

By the provision of the thickened edge 120 provided by the peripheral flange 28 which, as shown in Fig. 9, extends beyond the spring retainers 33 and the index cards h held thereby, the latter are adequately protected against displacement and injury as the holders B are swung back and forth from one position to the other in the use of 125 the device.

If desired, the index holders B may be 130 constructed to carry index cards or strips upon both sides, in which case two entirely different and distinct sets of index material

may be accommodated in one frame A, one set being read from one side of the frame and the second from the other side. Tabs 40 are adapted to index both sets since index cards may be inserted under sheath 43 on both sides of the tab.

I claim:

1. The combination with a frame having a rod mounted therein, of an index panel 10 comprising a sheet metal back, a peripheral integral flange projecting from one side thereof, said back and said flange having an opening through which said rod passes whereby said panel may swing in a plane 15 substantially perpendicular to said rod, and means independent of the flange for retaining index elements, said flange serving to protect the index elements on said panel in its swinging movement.
2. The combination with a frame having a rod mounted therein, of an index panel 20 comprising a sheet metal back having an integral marginal flange forming a closed channel, a filler in said channel, and an eyeleted opening through said flange, filler and back in which the rod extends whereby said panel may swing in a plane substantially 25 perpendicular to said rod.
3. An index device comprising a frame 30 and a plurality of index panels pivoted in parallel juxtaposition to swing edgewise into and out of the frame, each panel having spacer means projecting from one face into contact with the next adjacent panel to hold 35 the index-carrying portions of the panels in spaced relationship throughout their swinging movement and means independent of said spacers for securing removable index elements to the frame.
4. An index device comprising a frame 40 and a plurality of index panels pivoted in parallel juxtaposition to swing edgewise into and out of the frame, each panel having a tubular marginal flange projecting from 45 one face into contact with the next adjacent panel to hold the index-carrying portions of the panels in spaced relationship throughout their swinging movement.
5. An index device comprising a frame 50 and a plurality of index panels pivoted in parallel juxtaposition to swing edgewise into and out of the frame, the panels having marginal flanges projecting from their faces into contact with the next adjacent panels to hold 55 the index-carrying portions of the panels in spaced relationship throughout their swinging movement, and means independent of said flanges for positioning and removably securing index elements to the panel.
6. An index device comprising a frame 60 and an index panel normally disposed therein, the marginal edges of the panel being bent to provide tubular flanges, a filler member within one of said flanges, and pivotal 65 means passing through the latter flange and the filler connecting the panel to the frame.
7. An index device comprising a frame and an index holding panel normally disposed therein, one edge of the panel having a tubular flange, a rigid filler within the flange, the flange and filler having aligned openings, an eyelet disposed within the openings forming a pivot bearing, and a pivot pin extending through the eyelet and connecting the panel to the frame. 70
8. An index device comprising a frame and an index holding panel normally disposed therein, the panel being provided with rolled edges, and means secured to the face of the panel between its edges for retaining removable index elements. 80
9. An index device comprising a frame, a plurality of index holding panels normally disposed in substantial parallelism within the frame, each panel having marginal spacer flanges, and means secured to the face of each panel intermediate its marginal flanges for retaining removable index elements. 85
10. An index comprising a series of parallel index panels, each panel having spacer elements to hold the index carrying portion of the panel spaced from that of the adjacent panel, and means independent of the spacer elements for removably securing index elements to the panel. 90
11. An index device comprising an index holding panel provided with thickened edge portions and means secured to the panel within the space defined by its thickened edge portions and independent of the latter for removably retaining index elements. 100
12. An index panel comprising a body portion of sheet material having a thickened edge, a strip of sheet material secured to the body portion of the panel, and means secured to said strip for removably holding index elements. 105
13. An index panel comprising a back formed of sheet material, a strip of sheet material fixedly secured at its central portion to the back at a point intermediate the opposite edges of the latter, and means secured to said strip for holding index elements. 110
14. An index panel comprising a back formed of sheet material having an inturned marginal flange, a strip of sheet material having its ends underlying opposed portions of said marginal flange, and means engaging lateral edges of the strip for holding removable index elements. 115
15. An index panel comprising a back formed of sheet material having an integral inturned marginal flange, a strip of sheet material having its opposite ends underlying opposed portions of said marginal flange, means securing the central part of the strip to the back of the panel, and means secured to the strip for holding removable index elements. 120

16. An index panel having a sheet metal back, a peripheral flange integral with said back projecting from one side thereof, said flange being shaped to form a closed channel, said flange and back being cut away at the corners, a bent corner wire filling the cut-away space at each corner and having reduced ends received in the flange channel, the portions of the flange and back adjacent the exposed portion of said corner wire being inwardly bent from both sides to clamp said corner wire in place. 5
17. An index panel having a sheet metal back, a peripheral flange integral with said back projecting from one side thereof, and reinforcing members at the corners wedged between said flange and said back, a portion of said members being exposed through a cut-away portion of the flange, said exposed portion fitting the outlines of the panel and forming the corner. 10
18. An index panel having a sheet metal back, a peripheral flange integral with said back projecting from one side thereof, and reinforcing members at the corners wedged between said flange and said back, a portion of said members being exposed through a cut-away portion of the flange, said exposed portion fitting the outlines of the panel and forming the corner, and inwardly bent tongues on said flange and said back engaging said members to retain them in position. 20
19. An index panel having a sheet metal back, a plurality of strips fast on said backs, and elongate clips hooking under opposite edges of said strips for removably holding index material upon said strips. 30
20. An index panel having a sheet metal back, a peripheral flange projecting from one face of said back, a plurality of strips fast on said back in the space defined by said flange, elongate clips hooking under opposite edges of said strips for removably holding index material upon said strips, said strips being so positioned relative to each other and to said flange that the clips are retained against displacement by abutting each other and said flange respectively. 40
21. An index panel blanked from sheet metal and having an inturned marginal flange, a plurality of reinforcing strips mounted on said holder and having their ends extending beneath said flange, and elongate clips hooking under opposite sides of said strips for removably holding index material thereon. 50
22. An index panel blanked from sheet metal and having an inturned marginal flange, a plurality of reinforcing strips mounted on said holder and having their ends extending beneath said flange, and elongate clips hooking under opposite sides of said strips for removably holding index material thereon. 60
- ends extending beneath said flange, and elongate clips hooking under opposite sides of said strips for removably holding index material thereon, said clips being retained against displacement by being in abutting relation with each other and with said flanges respectively. 65
23. An index panel having a sheet metal back, the peripheral portion of said back being bent over upon itself to form an integral flange, a reinforcing strip riveted to said back and having its ends extending beneath said flange, and spring clips extending under opposite sides of said strips for removably holding index material thereon. 70
24. The combination with a frame having a rod mounted therein, of an index panel mounted on said rod for swinging movement into and out of said frame, said panel having a marginal flange and means adapted to be grasped to swing said panel to extended position comprising a tab having a bent end hooked under said flange and a portion having frictional engagement with the outer edge of the flange. 80
25. An index panel having an inturned marginal flange and a tab comprising a part disposed beneath said flange and a part engaging the outer edge of the flange, and means for securing a removable indexing element to the tab. 90
26. An index panel having an inturned marginal flange, a tab comprising a hook member disposed beneath said marginal flange and a part frictionally engaging the outer edge surface of the flange, a transparent sheath enclosing the tab, and an index element disposed between the sheath and one wall of the tab. 95
27. An index panel having an inturned marginal flange, and a tab having a portion interlocked with the flange and a tubular portion projecting beyond the edge of the flange, a transparent sheath enclosing the projecting portion of the tab and bowing out from one wall thereof, an index slip interposed between the sheath and tab, and means holding the slip in substantial contact with the bowed portion of the sheath. 105
28. An index panel having a tab secured thereto, a transparent sheath enclosing said tab and having a portion bowed out from the adjacent wall of the tab, an index slip interposed between the sheath and said wall, and a resilient member for holding the slip in substantial contact with the inner surface of the bowed portion of the sheath. 110

Signed by me at Boston, Mass., this 20th day of March 1922.

JAMES H. RAND.
